US0D1109069S

(12) **United States Design Patent** (10) **Patent No.:** **US D1,109,069 S**
(45) **Date of Patent:** **** Jan. 13, 2026**

(54) **END CLAMP FOR SOLAR PANEL**

(71) Applicant: **JING-XIN SOLAR LTD.**, Tainan (TW)

(72) Inventor: **Ching-Lung Yang**, Tainan (TW)

(73) Assignee: **Jing-Xin Solar Ltd.**, Tainan (TW)

(**) Term: **15 Years**

(21) Appl. No.: **29/924,244**

(22) Filed: **Jan. 18, 2024**

(51) **LOC (15) Cl.** **25-01**

(52) **U.S. Cl.**

USPC **D13/102**; D8/394

(57) **CLAIM**

The ornamental design for an end clamp for solar panel as shown and described.

DESCRIPTION

FIG. 1 is a first perspective view of an end clamp for solar panel showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a second perspective view thereof.

1 Claim, 8 Drawing Sheets
